(57) **CLAIM**

The ornamental design for a game console switch base, as shown and described.

DESCRIPTION

FIG. 1 is a front, top and right side stereoscopic view of a game console switch base, showing my new design; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The product is switch base for game console with Type-C port.

The broken lines in the drawings illustrate the portions of the game console switch base, which form no part of the claimed design.
